UNITED STATES PATENT OFFICE.

MICHAEL KATZMAREK, OF DULUTH, MINNESOTA.

WRENCH.

1,350,315.

Specification of Letters Patent. Patented Aug. 24, 1920.

Application filed September 9, 1918, Serial No. 253,294. Renewed February 12, 1920. Serial No. 358,129.

To all whom it may concern:

Be it known that I, MICHAEL KATZMAREK, a citizen of the United States, residing at Duluth, county of St. Louis, State of Minnesota, have invented a certain new and useful Improvement in Wrenches, of which the following is a specification.

This invention relates to improvements in wrenches and particularly to types known 10 as ratchet wrenches.

The principal object of the invention is to provide a neat and compact type of wrench capable of operating upon different sized bolt heads or nuts so as to turn the 15 same, even when positioned in contracted locations.

A further object is to provide means by which the head or part contacting with the nut or bolt head to be turned, may be 20 readily removed, and others of different sizes or shapes substituted.

These and other like objects are attained by a novel construction and combination of parts hereinafter described, and shown in 25 the accompanying drawings, forming a material part of this disclosure, and in which:—

Figure 1 is a plan view of a wrench made in accordance with the invention;

Fig. 2 is a side or edge view of the same; 30 Fig. 3 is a fragmental sectional view, taken on line 3—3 of Fig. 1;

Fig. 4 is a perspective view showing one of the side plates by which the interchangeable heads are maintained within the wrench 35 body;

Fig. 5 is a perspective view of the screws used in connection with the plates shown in Fig. 4;

Fig. 6 is an enlarged fragmental plan view 40 of the wrench body, partially broken away in order to show the interior;

Fig. 7 is a perspective view showing a portion of the wrench handle, and a modified form of plate holding elements;

Fig. 8 is a perspective view of the head or nut engaging elements;

Fig. 9 is a perspective view of the plunger actuating spring; and

Fig. 10 is a perspective view of one of 50 the plungers by means of which the head or nut engaging element is actuated.

In the drawings the numeral 10, represents the handle, having the recesses 55 formed upon opposite sides in order to lighten the implement.

The operative end or front of the imple-

ment is formed within a circular opening 12, leading to which is a passage 14, between the extreme ends of the jaws 15. Receivable within the opening 12, is a head or nut 60 engaging implement 17, formed with exterior ratchet shaped teeth 18, and containing an opening 20, suited to engage the heads of bolts, nuts and the like which it is desired to turn.

Extending outward from opposite sides of the head 17, are raised cylindrical hubs 21, the same extending beyond the thickness of the wrench head 13 and engageable within the openings 20, of plates 23, formed 70 with rearwardly extending shanks 24, secured to the sides of the wrench body 10, by screws 25, the same being threaded into the shank of the implement, and having an enlarged shoulder 26, adjacent to the head 75 27, so as to permit the screws to be firmly secured, the same passing through the slots 28, which have shouldered recesses 29 for the reception of the shoulders 26 of the screws.

Secured in the rear ends of the plates 23, are raised projections 30, by means of which the plates can be moved so as to engage with the head 17, or retracted therefrom, when it is desired to change from one head to 85 another.

In order to hold these plates from inadvertent movement, and as a modified form of construction, a hole is drilled transversely through the handle 10, as shown in Fig. 7, 90 in which is contained a spiral compression spring 32, pressing outwardly opposed pins 33, the same entering into recesses formed below the projections 30, when the plates are in an operative position. (Not shown.) 95

Also formed through the head 13, of the wrench, are openings 35, having shoulders 36, in contact with which are corresponding shoulders 37, formed with the plungers 38, which have a beveled tooth 39, at their 100 extreme inner ends, the same being engageable with the teeth 18, of the heads 17. From the opposite end of the plungers extend tenons 40, engageable in slots 42, of the spring elements 43, which are secured to the 105 edge of the handle by screws 44 passing through the openings 45.

Either one or both of the plungers are held in intimate contact with the teeth of the head by the springs 43 so that upon a slight oscillating movement being transmitted by movement of the handle, the heads

17, are rotated, and in either direction according to the position of the head in the handle.

In operation, the head being placed upon 5 a nut or bolt to be turned, the handle is operated in an obvious manner. If it is desired to change from one head to another or to change from a right to a left hand wrench, or vice versa, both the plates 24 are 10 moved rearwardly, permitting the head 17 to pass laterally outward from the wrench head 13, and be turned over, or to be replaced with another having a different size or shape of opening.

15 Having thus described my invention, what I claim as new and desire to secure by Letters Patent, is:

1. A wrench having a handle with an enlarged head, a gripping head rotatably engaged therein, teeth formed on the periphery of said gripping head, plungers operable in said enlarged head adapted to engage said teeth, cylindrical hubs on the opposite faces of said gripping head, plates slidable on said 20 handle having semi-circular recesses on their forward ends, the forward ends of said plates projecting over marginal portions of the said gripping head and having the said cylindrical hubs snugly engaged in 25 30 the said recesses thereby holding said gripping head in position, and means permitting the operation of said plates whereby

either or both may be retracted from said gripping head.

2. A wrench having a recessed handle 35 provided with an enlarged head containing a circular bore transversely therethrough, a gripping head suited to rotate in said bore, teeth formed on the periphery of said gripping head, said gripping head being receptive of articles to be turned, cylindrical hubs extending outwardly from the opposite faces of said head, plates arranged slidably at the sides of said handle and having recessed ends adapted to project over the marginal portions 40 of the said faces to engage the said hubs, means for holding said plates slidably on said handle, plungers slidably in said enlarged head and engaging the said teeth, said plungers having tenons on their outer 45 ends, and a pair of flat springs secured to the said handle and inclosing the enlarged head of the latter on opposite sides and having recesses complementary to the said tenons in which the latter engage. 50 55

In testimony whereof, I have signed my name to this specification in the presence of two subscribing witnesses, this 21st day of December, 1917.

MICHAEL KATZMAREK.
